UNITED STATES PATENT OFFICE.

JOHN METCALFE, SR., OF BROWNSVILLE, PENNSYLVANIA.

TROLLEY-POLE.

1,317,932.

Specification of Letters Patent.

Patented Oct. 7, 1919.

Application filed August 3, 1917. Serial No. 184,274.

To all whom it may concern:

Be it known that I, JOHN METCALFE, Sr., a citizen of the United States, residing at Brownsville, in the county of Fayette and State of Pennsylvania, have invented certain new and useful Improvements in Trolley-Poles; and I do hereby declare the following to be a full, clear, and exact description of the invention, such as will enable others skilled in the art to which it appertains to make and use the same.

This invention has for its object to provide an improved trolley pole for mine motors which is so constructed as to collapse or fold up when the pole leaves the wire and strikes a projection on the roof, so as to prevent breaking of the pole or damage to the motor or injury to the operator in consequence of the pole's impact on a roof projection.

Another object is the provision of a collapsible pole of this character which may be repaired and replaced in use with a minimum expenditure of labor and time.

With this and other objects in view, the invention consists in the novel construction, combination and arrangement of parts as will be hereinafter specifically described, claimed and illustrated in the accompanying drawing, in which—

Figure 1 represents a side elevation of the improved trolley pole,

Fig. 2 represents an enlarged longitudinal sectional view at right angles to Fig. 1.

Fig. 3 represents a perspective view of one terminal of one of the trolley pole sections detached,

Fig. 4 represents a detail sectional view on the line 4—4 of Fig. 1,

Fig. 5 is a side elevation of a modified form of the device.

Referring to the drawing in detail, wherein similar reference numerals designate corresponding parts throughout the several views, the numerals 8 and 9 indicate the inner and outer sections of the trolley pole, the inner sections 8 being adapted for connection with the usual type of spring actuated pole support or holder, and the outer section 9 carrying the harp or bracket 10 in which the trolley wheel 11 is rotatably supported.

The opposed side faces of the adjacent ends of the sections 8 and 9 are cut away, as indicated at 12. The reduced and overlapping ends of the sections 8 and 9 are provided with alined slots 13, receiving the pivot pin or bolt 14, which is provided with

a nut 15, a hole for linch pin to hold washer, or other means of securing the sections and permit swinging movement of the outer section 9 relative to the inner section 8. As clearly shown in Fig. 1, the shoulders 16 defined by cutting away the adjacent terminals of the sections, are inclined in opposite directions so as to permit the outer section 9 to be folded back toward the inner section 8, as shown in dotted lines in Fig. 1.

The two sections 8 and 9 are normally retained in alinement by frangible tapered pins 17, which are fitted in alined apertures 18 formed in the reduced terminals of the pole sections. The pins 17 may be constructed of wood, or any other suitable material, which will be readily broken when the pole leaves the wire and strikes the roof. The impact of the blow of the wheel carrying end of the pole against the roof, or timbers of the mine readily breaks or severs the pins 17, allowing the outer section 9 to fold back to the dotted line position shown in Fig. 1 and instead of the danger of a roof falling caused by the timbers being broken out by the rigid pole, it is avoided by the severed pins and folding pole. Also the delays resulting from the broken poles are ended by this invention. The motorman instead of going to the shop for a new pole, puts his hand into his pocket for his punch, knocks out the broken pins with his hitching pin and is again ready in a couple of minutes by driving in two new pins. All danger to motormen, (which are many) resulting from the breaking of poles, are by this device eliminated, making this pole true to its title, a safety collapsible, or sectional trolley pole. The aforesaid sectional joint of this safety pole can be manufactured out of malleable iron, aluminum or any other suitable material and can be cast so that the sections 8 and 9 can be inserted and held in correct alinement by a bolt going through the casting and the pole inserted. This casting would be an almost indestructible and ever ready means of averting trolley pole accidents. While the pole itself can be made of wood, it is usually desirable to make the joint of castings as described above.

What I claim is:—

1. A trolley pole including a plurality of sections having the adjacent ends reduced and overlapped, means pivotally securing the adjacent overlapped ends of the central portion thereof, and frangible means extending

through the overlapped ends on each side of the pivotal point to normally maintain the sections in alinement with each other.

2. A trolley pole including a plurality of 5 sections having the adjacent ends reduced and overlapped, means pivotally securing the adjacent overlapped ends at the central portion thereof, said sections having alined tapered openings formed therein on each 10 side of the pivot point, and tapered frangible pins removably fitted in said tapered openings.

3. A trolley pole including a plurality of

sections having the adjacent terminals reduced and slotted, means extended through 15 the slots in the reduced ends pivotally connecting the sections, and frangible pins fitted in the overlapped ends and normally maintaining the sections in alinement with each other.

20 In testimony whereof I affix my signature in presence of two witnesses.

JOHN METCALFE, SR.
